UNITED STATES PATENT OFFICE.

ROBERT Y. BARROWS, OF RUTHERFORD, AND GEORGE V. STRAHAN, OF NEWARK,
NEW JERSEY.

DESIGN FOR A GLOBE FOR LIGHTING-FIXTURES.

49,757.

Specification for Design.

Patented Oct. 17, 1916.

Application filed August 24, 1916. Serial No. 116,737. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for a Globe for Lighting-Fixtures, of which

the following description, in connection with the accompanying drawing, is a specification.

The single figure of the drawing is an elevation of a globe for lighting fixtures, showing our new design.

We claim as our invention:

The ornamental design for a globe for lighting fixtures, as shown.

ROBERT Y. BARROWS.
GEORGE V. STRAHAN.
